(57) **CLAIM**

The ornamental design for a loofah sponge with attached adjustable straps, as shown and described.

DESCRIPTION

FIG. 1 is a perspective view of the loofah sponge with attached adjustable straps showing my new design;

FIG. 2 is a front elevational view thereof;

FIG. 3 is a back elevational view thereof;

FIG. 4 is a top plan view; and,

FIG. 5 is an enlarged left side elevational view thereof, the opposite side being a mirror image thereof.
